Primary Examiner — Marianne Pandozzi(57) CLAIM

The ornamental design for a beverage dispensing machine, as shown and described.

DESCRIPTION

FIG. 1 is a front view of a beverage dispensing machine showing our new design;

FIG. 2 is a right side view thereof, the left side being a mirror image thereof;

FIG. 3 is an top view thereof.

FIG. 4 is a back view thereof; and,

FIG. 5 is a bottom view thereof.

The broken lines in the drawings are included for the purpose of illustration and form no part of the claimed design.
